Filed Mar. 11, 1965, Ser. No. 84,211

Term of patent 14 years

(Cl. D26—14)

FIG. 1

FIG. 2

FIG. 3

FIG. 5

FIG. 6

FIG. 4

FIG. 7

FIG. 1 is a side elevational view of a pickup cartridge housing embodying my new design;

FIG. 2 is a top plan view thereof;

FIG. 3 is a bottom plan view thereof;

FIG. 4 is an opposite side elevational view;

FIG. 5 is a rear elevational view thereof;

FIG. 6 is a front elevational view thereof;

FIG. 7 is a longitudinal sectional view taken along line 7-7 in FIG. 5.

The characteristic feature of my design resides in the combination on the pickup cartridge housing as shown and having an arrowhead-like configuration with an outwardly flaring taper on all four sides and having a U-shaped opening extending rearwardly across the leading edge, all as shown.

I claim:

The ornamental design for a pickup cartridge housing, as shown and described.
